CASE FOR AN ELECTRIC SHAVER

Erdick H. Nelson, Naperville, Ill.

Application October 1, 1953, Serial No. 27,034

Term of patent 14 years

(Cl. D58—12)

To all whom it may concern:

Be it known that I, Erdick H. Nelson, a citizen of the United States, resident of Naperville, Du Page County, Illinois, have invented a new, original, and ornamental Design for a Case for an Electric Shaver, of which the following is a specification, reference being had to the accompanying drawing, forming a part thereof, in which:

Fig. 1 is a front elevational view of a case for an electric shaver, embodying my new design;

Fig. 2 is a side elevational view thereof, the opposite side being the same as that shown;

Fig. 3 is a rear elevational view thereof;

Fig. 4 is a top plan view thereof;

Fig. 5 is a side elevational view of the case in open position, taken on a reduced scale; and

Fig. 6 is a front perspective view of the case in open position.

I claim:

The ornamental design for a case for an electric shaver, substantially as shown and described.
